CASING PUMP FOR OIL WELLS AND THE
LIKE

Hubert D. Collins, Tulsa, Okla.

Application May 22, 1940, Serial No. 336,501

3 Claims. (Cl. 103—221)

This invention relates to new and useful improvements in pumping mechanisms for flowing oil wells and the like. It deals particularly with well pumps of the type known as casing pumps, which are located in place inside of the usual well casing and make use of the casing for conducting oil to the ground surface.

A desirable type of casing pump construction, as employed heretofore in oil well flowing operations, includes a working barrel for the pump piston, an expandable packer of rubber composition or the like connected through a drain sleeve with the working barrel, a pump head carrying a mandrel that is movable into the packer to expand the same into sealing engagement with the well casing, a drain tube depending from the mandrel toward the working barrel, and the usual string of sucker rods connected with the piston. The pump mechanism is lowered into the well casing by the sucker rods, and when it reaches the desired pumping position (after having been located in place by suitable means provided for that purpose) the mandrel is moved into the packer to seal the pump in the well. Thereafter, the sucker rods are reciprocated to move the piston in the working barrel and thus force oil upwardly through the working barrel, the drain tube, the pump head and the well casing.

When it is desired to remove a pump of this type from the well, it is necessary to lift the mandrel out of the packer so that the seal between the latter and the well casing may be broken. The column of oil lying between the pump proper and the ground surface, however, still bears on the packer and hinders withdrawal of the pump. It will be understood that a large amount of oil is held in the casing of a deep well, so that the hydrostatic pressure may be very great. Although it has been proposed to overcome the attendant difficulties by providing drainage ports below the packer, this expedient is of limited effectiveness due to the restricted space which may be available, the resilient or flexible construction of the packer and the high hydrostatic pressures that may prevail.

It is therefore the object of this invention to provide a new and improved casing pump construction which equalizes hydrostatic pressure on the packer and gives positive drainage of liquid through the pump itself after the mandrel has been unseated, thereby increasing the efficiency of the pump while retaining all of the desirable features of the aforesaid known type of pump construction.

Other objects and advantages of my invention will be apparent from the following detailed description of a preferred embodiment thereof, when considered in connection with the accompanying drawing, in which

Figure 1 and Figure 1a are longitudinal views, partly in cross section, showing, respectively, upper and lower portions of an illustrative pump mechanism as located in a well casing with the packer unsealed;

Figure 2 is a transverse cross section substantially along line 2—2 of Figure 1;

Figure 3 is a transverse cross section substantially along line 3—3 of Figure 1; and

Figure 4 is an enlarged longitudinal cross section showing part of the mechanism of Figure 1 with the packer sealed against the well casing, as when the pump is ready for operation.

I have found that the efficiency of casing pumps may be improved and that difficulties incident to the withdrawal of such pumps from oil wells may be substantially reduced by providing the pump with means for effecting positive drainage of liquid therefrom when the mandrel has been unseated from the packer. In accordance with my invention, the pump is constructed to operate in known manner during the location, sealing and operation of the same in the well; but when the mandrel is raised out of the packer to break the seal between the latter and the casing, a new arrangement of drainage facilities comes into operation which gives positive drainage of liquid from the drain tube and avoids the objectionable pressure conditions and the inefficient drainage that have been characteristics of known casing pump constructions.

The new pump construction is illustrated in Figures 1 and 1a as the parts are associated when the pump is ready to be sealed in the well casing 10, or to be withdrawn from the casing after the completion of pumping operations. A pump rod 12 extending into the pump is connected with the usual string of sucker rods (not shown), or the equivalent. The lower end of the pump rod (Figure 1a) is connected to a pump piston or sucker 14 which carries a travelling valve 16 and sealing rings or gaskets 18 and which is reciprocable by rod 12 in a working barrel 20. A valve housing 22 at the lower end of the working barrel encloses a standing valve 24 through which oil is admitted from the well into the working barrel on the upward stroke of piston 14.

An expandable packer 30, of rubber or other similar resilient material, is located near the

upper end of the pump and is connected with the upper end of the working barrel 20 by tubular means including, in the illustrated form, a flanged ring 32, a drain sleeve 34 and suitable tubular coupling sleeves 36 and 38. The packer 30, as shown in Figure 1, is normally spaced inwardly from the inside surface of the well casing 10. Above the packer and surrounding rod 12 is a pump head 40 which terminates at its lower end in a mandrel 42 having a tapered cam surface. The head 40 provides a hollow space 44 surrounding the pump rod, which space communicates with the well casing above the packer through lateral ports 46. The mandrel 42 is adapted to enter packer 30 and to force the same into sealing engagement with the casing 10, as shown in Figure 4. Depending from mandrel 42 in spaced relation to the pump rod 12 is a drain tube 48, which is of such length as to extend substantially to the working barrel 20 when the pump is located and sealed in operating position. It will be observed that the drain tube 48 extends downwardly from mandrel 42 inside of the packer 30 and inside of the tubular means 32, 34, 36 and 38.

As shown in Figures 1, 3 and 4, cooperating means are provided on drain tube 48 and drain sleeve 34 for limiting axial movement of the mandrel relative to the packer. In the illustrated form, such means includes spaced recesses or slots 50 in sleeve 34 and fitting tongues or lugs 52, on drain tube 48, which are movable vertically to a limited extent in the slots 50. At a location above slots 50, the drain sleeve 34 carries a sealing ring or packing 54 which engages the outer wall of the drain tube 48 and prevents entrance of liquid into the underlying intervening space. Further sealing means are provided between the drain tube 48 and the aforesaid tubular means, in the form of a packing ring 56 that is located in an annular recess between sleeves 36 and 38 in position to engage the outer surface of the drain tube. The packing 56 is preferably a chevron packing.

In accordance with this invention, as shown in Figures 1, 2 and 4, the tubular means connecting the packer 30 with the working barrel (in this instance at sleeve 36), is provided above the packing ring 56 with a series of radial drainage ports 60 which lead from the inside of sleeve 36 to the annular space between the outer surface of sleeve 36 and the well casing 10. For cooperation with these drainage ports 60, the drain tube 48 also is provided with a series of radial drainage ports 62. As shown in Figures 1, these ports 62 are so located that when the tongues 52 are positioned near the upper ends of their respective slots 50, that is, when the pump head 40 and mandrel 42 have been withdrawn from the packer 30, the ports 62 of the drain tube register with the ports 60 of sleeve 36 and thus provide openings for positive drainage of liquid from the drain tube through the same and sleeve 60 and into the surrounding space of the well casing. When, however, the pump head and mandrel are moved downwardly to a position sealing packer 30 against the casing 10, the drainage ports 62 of the drain tube pass downwardly to a position below the packing 56. This position of the pump, which corresponds to the operating position, is shown in Figure 4. It will be understood that the packing 56 then serves to block flow of liquid from ports 62 to ports 60 and that the pump, when so assembled and operated, causes liquid to be forced upwardly

through the working barrel, the drain tube, the pump head and the well casing without leakage or loss of pressure.

In the use of the new pump construction, the 5 pump is lowered into the well casing by a string of sucker rods in the usual manner, mandrel 42 being spaced from packer 30 with tongues 52 at the upper limits of slots 50, as shown in Figure 1. When the pump has reached the desired pumping 10 position, it is located in place either by resting upon a suitable preformed obstruction or by the use of a suitable anchoring device of conventional construction (not shown). The weight of 15 the working barrel assembly is then removed from the tongues 52, and upon further downward movement of the rods the tapered mandrel 42 moves into packer 30 and seals the same against the casing. In this position, as shown in Figure 4, the drain tube 48 also is sealed with 20 respect to the surrounding tubular means 32, 34, 36 and 38 by reason of the packings 54 and 56 and the seal between mandrel 42, packer 30 and the well casing 10. Reciprocation of the pump piston 14 then forces liquid into the working barrel 20 through standing valve 24, and from the working barrel the liquid is forced through travelling valve 16 and upwardly through the drain tube, pump head and well casing.

Upon termination of pumping operations, the 25 pump assembly may be removed from the well by lifting the pump rods above their normal working position so that certain lugs 13 on rod 12 strike the upper part of head 40. Further lifting of the rods raises head 40 and drain tube 48 and forces mandrel 42 out of packer 30, allowing the seal between the packer and the well casing to be broken. As the drain tube moves 30 independent of the working barrel assembly until the tongues 52 reach the upper limits of slots 50, the drainage ports 62 of the drain tube pass above packing 56 and thereupon establish direct communication between the inside of the drain tube and the surrounding casing through the drainage ports 60 in sleeve 36. This positive 35 drainage of liquid from the drain tube equalizes hydrostatic pressure on the packer and effects a comparatively rapid drainage of liquid from the pump, thereby permitting the pump readily to be withdrawn from the well and avoiding difficulties that have been encountered heretofore.

As shown in Figures 1 and 4, the drain sleeve 34 may include drainage ports 70 at a point located above the sealing ring 54. These ports may accommodate a certain amount of drainage 40 inside the packer 30 after the mandrel has been unseated, according to known practice.

While I have illustrated and described details of a particular embodiment of my invention, I understand that the invention may be embodied in other forms of construction without restriction to these particular details. I therefore desire that the invention be accorded a scope commensurate with its novel contributions to the art, as intended to be set forth in the appended 45 claims.

I claim:

1. In a well pump, a working barrel having a standing valve adjacent its lower end and a piston with travelling valve reciprocable therein by means of a suitable pump rod, an expansible packer above said working barrel, tubular means connecting said packer with said working barrel, a mandrel movable into said packer to expand the same and seal the pump in a well, a drain tube depending from said mandrel inside of said

packer and said tubular means, drainage means opening through the wall of said tubular means, sealing means between the drain tube and the tubular means below said drainage means, and drainage means opening through the wall of said drain tube, the last-recited drainage means being located below said sealing means when the mandrel is positioned within the packer and above said sealing means when the mandrel is withdrawn from the packer.

2. In a well pump including a working barrel, a pump piston reciprocable in the barrel by a suitable pump rod, an expandible packer connected with the upper end of said working barrel by intermediate tubular means, a mandrel movable into said packer for expanding the same into sealing engagement with a well casing and a drain tube depending from the mandrel into said tubular means, cooperating means on said drain tube and said tubular means for limiting axial movement of the mandrel relative to the packer, liquid drainage ports in the wall of said tubular means, sealing means between said drain tube and said tubular means below said ports,

and liquid drainage ports in the wall of said drain tube, said last-recited ports being located below said sealing means when the mandrel is positioned within the packer and above said sealing means when the mandrel is withdrawn from the packer.

3. In a well pump having a mandrel, a drain tube depending from the mandrel, tubular means surrounding the drain tube and an expandible packer carried by the upper end of said tubular means to be expanded into sealing engagement with a well casing by downward movement of said mandrel, cooperating tongue and slot means on said drain tube and tubular means for limiting axial movement of the former relative to the latter, radial drainage ports in said tubular means below said tongue and slot means, sealing means between said tubular means and said drain tube below said drainage ports, and radial drainage ports in said drain tube positioned to register with the aforesaid drainage ports when said mandrel is located above said packer.
